CLAIM

The ornamental design for a curling iron barrel, as shown and described.

DESCRIPTION

FIG. 1 is a top plan view of a curling iron barrel showing our new design;

FIG. 2 is a left side elevational view thereof;

FIG. 3 is a bottom plan view thereof;

FIG. 4 is a right side elevational view thereof;

FIG. 5 is a rear elevational view shown on an enlarged scale;

FIG. 6 is a front elevational view thereof; and

FIG. 7 is a cross-sectional view taken on the line 7—7 of FIG. 2.

The broken line showing of the tip, handle, stand, thumb or finger press, and cord of a curling iron is for illustrative purposes only and forms no part of the claimed design.
